BODY WARMER

Paul A. Siple, Arlington, Va.

Application June 11, 1952, Serial No. 293,025

8 Claims. (Cl. 126—204)

(Granted under Title 35, U. S. Code (1952),
sec. 266)

1

The invention described herein, if patented, may be manufactured and used by or for the Government for governmental purposes, without the payment to me of any royalty thereon.

My invention relates to a body-warming device.

A primary object of the invention is to provide a jacket for imparting heat to the body of the wearer and including self-contained means for generating heat.

A further object is to provide a body-warming jacket having a heated liquid circulating system arranged next to the body so that heat from liquid is transferred by conduction and radiation to the body.

A further object is to provide a body-warming garment having a warm liquid circulating system, and means actuated by breathing for causing the liquid to circulate through the system.

A further object is to provide a body-warming jacket which is equipped with one or more liquid heating reservoirs which surround chemical or other self contained heating units, so that the liquid in the reservoirs is heated before it is circulated about the body.

A further object is to provide a body-warming garment so constructed that a large area of the body may be effectively warmed.

A still further object of the invention is to provide a device of the above-mentioned character which is simplified in construction, lightweight and inexpensive to manufacture.

Other objects and advantages of the invention will be apparent during the course of the following description.

In the accompanying drawings, forming a part of this application, and in which like numerals are employed to designate like parts throughout the same,

Figure 1 is a front elevation of a body-warming jacket embodying my invention, part in section.

Figure 2 is a rear elevation of the jacket, part broken away,

Figure 3 is an enlarged horizontal section taken on line 3—3 of Figure 1,

Figure 4 is an enlarged longitudinal vertical section taken on line 4—4 of Figure 1, parts broken away,

Figure 5 is a side elevation of the jacket,

Figure 6 is a plan view of the jacket in a flat extended position,

Figure 7 is an enlarged fragmentary sectional view through a tube of the device, and showing a removable filling cap mounted thereon, and,

Figure 8 is an enlarged fragmentary vertical section through a heat exchange tube of the

2

jacket and showing a one-way check valve mounted within the tube.

In the drawings, where for the purpose of illustration is shown a preferred embodiment of my invention, the numeral 10 designates generally a flexible fabric sheet or blank which forms the body portion of the jacket. The sheet 10 is preferably formed of canvas duck, or some similar material which is stretch resistant. The sheet 10 is generally rectangular as shown in Figure 6, and adapted to be folded transversely near its longitudinal center to form a front 11 and back 12 of the jacket. The jacket front 11 is split longitudinally at 13, to form a front button or snap closure 14 as shown in Figure 1. A neck-receiving opening 15 is formed centrally in the sheet 10, and the opposite longitudinal edges of the sheet are tailored at 16 to form arm-receiving openings.

20 To aid in adjusting the jacket 10 to fit various individuals, the sheet 10 is further provided near its opposite longitudinal edges with rows of longitudinally spaced lacing eyelets 17, the rows extending from the bottoms of the arm openings to the lower end of the jacket, Figure 1. Suitable lacing 18 is provided for coaction with the eyelets 17 to draw the jacket tightly about the body of the wearer similar to a corset, for a purpose to be described.

25 30 Heat transfer means for the jacket are provided, which comprise a plurality of generally vertical flexible tubes 19 of rubber or the like, arranged next to the inner side of the jacket, and extend from the top of the jacket to the lower end thereof. An upper flexible header or rubber tube 20 is arranged upon the inner side of the jacket and extends about the rear of the neck opening 15, and includes side branches 21 which lie beneath the shoulders of the jacket, Figure 1.

35 40 The outer end 22 of one side branch 21 is permanently closed, while the outer end of the other branch 21 carries a removable screw-threaded liquid-tight plug 22', Figure 7. The upper ends of the tubes 19 are permanently connected in the header 20, in any preferred manner.

45 A lower flexible header section or rubber tube 23 is disposed upon the inner side of the back 12 and extends along the lower edge thereof and has its ends 24 permanently closed. Lower flexible header sections 25 and 26 likewise extend adjacent to the lower edge of the jacket front 11 at the inner side of the same, and have their ends 26' permanently closed. The lower ends of the tubes 19 next to the back 12 are permanently connected in the lower header section 23,

and the lower ends of the tubes 19 adjacent to the jacket front 11 are permanently connected in the header sections 25 and 26 in a preferred manner to form liquid-tight joints.

The several heat transfer tubes 19 are formed at longitudinally spaced intervals to provide enlarged compressible bulbs 27, integral therewith, and each tube 19 preferably has about 6 of the elastic bulbs 27, although the number may be varied as desired. The bulbs 27 of adjacent tubes 19 are staggered vertically, as shown in Figures 1 and 2, so that the several rows of bulbs interfit, and a maximum number of the bulbs may be employed for covering a maximum area of the body.

The headers 20, 23, 25 and 26 are secured to the inner side of the jacket in any preferred manner, such as by heat resistant waterproof cement, or by tapes, or the like, not shown. The headers lie against the inner face of the jacket, as shown. The enlarged bulbs 27 contact the inner face of the jacket, and are secured thereto at 28 by suitable cement or the like, Figure 4. The bulbs 27 maintain the vertical tubes 19 spaced slightly from the inner surface of the jacket, as shown. The tubes 19 may also be connected with the jacket 10 by means of tapes or cords, not shown, if desired.

The bulbs 27 may directly contact the body of the wearer, but in some instances the heat produced by the chemical or catalytic heaters may be too intense for comfort. To offset this, small pads of sponge rubber, fabric, felt or the like, not shown, may be cemented to the inner sides of the bulbs 27, and these pads may contact the body and insulate the same somewhat against the direct effect of the heat from the bulbs.

Near the lower ends of the heating tubes 19, and below the lowermost bulbs 27, all of the tubes are provided with one-way check valves 30, Figure 8, which permit the liquid within the tubes 19 to flow downwardly therein, but prevent the liquid from flowing upwardly from the lower ends of the tubes 19. The valves 30 are preferably membrane flutter valves as shown in Figure 8.

A plurality of flexible liquid-heating reservoirs or bags 31 of rubber or the like are arranged upon the outer side of the jacket 10, and preferably a pair of the reservoirs 31 is arranged at the front and back of the jacket. The reservoirs 31 are somewhat elongated vertically, and relatively flat, so that they will tend to lie against the body. Rubber tubes 32 and 33 lead from the tops and bottoms of the bags 31, for connection in the headers 21, 23, 25 and 26.

Each bag or reservoir 31 has an internal dry pocket 33' having an upper opening 34 for receiving a self-contained heater 35 of a preferred conventional type.

The heater 35 may be a catalytic heater, or a chemical heater of the type embodying a jacket or container for a chemical composition which generates heat in the presence of water, as a reactant. For example, I may use chemical heaters of the type shown in Patents 2,429,973; 1,760,102; 1,558,248 or 1,602,456. The heaters 35 are self-contained units, which are bodily removable through the openings 34 when they become exhausted. Where catalytic heaters are used, the openings 34 also serve to admit air, necessary for the operation of the heaters.

Since the bags 31 and their tubes 32 and 33 are disposed upon the outer side of the jacket, suitable openings 36' are formed in the sheet 10 for receiving the tubes 32 and 33, where the same are

connected with the headers 20, 23, 25 and 26. The arrangement is such that the heaters 35, when arranged in the pockets 33, are substantially completely surrounded by the liquid within the bags

31, and the heat given off by the chemical heaters is transferred to the liquid in the reservoirs by conduction. It should be mentioned here that walls of the bags 31, tubes 19, bulbs 27 and the several headers 20, 23, 25 and 26 are quite thin so that heat can readily pass through the same by conduction. If desired, the outer walls 37 of the bags 31 may be made somewhat thicker than the inner walls 38 next to the heaters 35, so that heat lost by conduction from the outer sides of the bags 31 is reduced. The inner walls 38 being thinner will more efficiently conduct heat from the heaters 35 to the liquid within the bags 31.

Each reservoir or bag 31 preferably has a slightly enlarged bulb portion 36 near its lower end and below the heater 35, which may be compressed manually to pump the liquid through the system with more speed than it would normally have due to breathing action by the wearer, and natural convectional circulation.

In use, the system including the tubes 19, headers 20, 23, 25, 26 and bags 31 is filled or substantially filled with water or some other suitable liquid, by removing the plug 22', and when the plug is securely replaced, the jacket may be donned. The lacing 18 is tightened so that the jacket is bound fairly tightly about the body and the bulbs 27 are slightly compressed between the body and fabric sheet 10.

When the heaters 35 are adjusted to give off heat, such heat is conducted through the inner walls 38 of the bags 31 to the liquid within the reservoirs 31. When the wearer of the jacket breathes normally, the bulbs 27 are continuously compressed and expanded, and this creates a pumping action which causes the liquid in the reservoirs 31 to circulate upwardly through the tubes 32 and into the upper header 20. The water then circulates downwardly through the tubes 19 and through the check valves 30 to the lower headers 23, 25 and 26, which in turn convey the liquid back to the lower ends of the bags 31, by way of the tubes 33. If it is desired to speed up the flow of liquid in the system, one or more of the bulb portions 36 may be alternately compressed and released, and this pumping action increases the velocity of the liquid through the system. Circulation in the system is also aided by convection, the warm liquid tending to rise from the bags 31, through the tubes 32. In this manner, the heated liquid flows continuously next to the body of the wearer and heat is transferred by conduction and radiation to the body. The check valves 30 prevent the liquid from circulating in the opposite direction through the system, as previously explained.

If desired, the jacket may also be used to cool the body. In such case a cooling substance such as ice or Dry Ice may be placed within the pockets 33, in which case the liquid coolant in the system should be one which will not freeze readily.

I also contemplate omitting one or more of the reservoirs 31, and the device may be used with a single pair of the reservoirs 31 or a single reservoir only, since the heaters 35 are capable of producing an intense heat. By employing more than one reservoir and heater, it is of course possible to generate more heat and to heat the body for a longer period of time. When a plurality of reservoirs and heaters are used, one chemical heater

at a time may be exhausted, and others adjusted to operate after the first heater is consumed or exhausted.

It is to be understood that the form of the invention herewith shown and described is to be taken as a preferred example of the same, and that various changes in the shape, size and arrangement of parts may be resorted to, without departing from the spirit of my invention or the scope of the subjoined claims.

Having thus described my invention I claim:

1. A body-warming garment including a body portion covering a substantial area of the body, tubes mounted upon the body portion and having compressible parts which bear against the wearer and are compressed when the wearer breathes, a liquid reservoir mounted upon the body portion and connected with the tubes and having a pocket formed therein, and a heating unit mounted within the pocket for transmitting heat to liquid contained within the reservoir and tubes.

2. A body-warming device comprising a flexible sheet to be arranged next to a portion of the body, tubes connected with the flexible sheet at the side of the same next to the body and having compressible parts for engagement with the body so that breathing compresses the parts, reservoir bags arranged upon the opposite side of the sheet and connected with the tubes for supplying liquid to the same and having pockets therein, heating units disposed within the pockets, and one-way check valves mounted within the tubes.

3. A body-warming device comprising supporting means to be mounted upon the body, a plurality of tubes carried by the supporting means and having enlarged compressible bulb portions for contact with the body so that the bulb portions are compressed during breathing, common headers connected with the opposite ends of the tubes, a reservoir bag carried by the supporting means and having opposite ends connected with the common headers and being provided with a pocket, and a self-contained heater mounted within the pocket for transmitting heat to a liquid contained within the reservoir bag, tubes and headers.

4. A body warming garment comprising a body portion for covering a substantial area of the body between the waist and shoulders, tubes secured to the body portion and disposed upon the inner side thereof next to the body and having compressible parts which bear against the body and are compressed when the wearer of the garment breathes, a self-contained heater mounted upon the outer side of the body portion, and a liquid container mounted upon the outer side of the body portion adjacent to the heater and arranged in thermal contact with the heater and communicating with the tubes, whereby heated liquid circulates through the tubes and warms the body as the wearer of the garment breathes.

5. A body warming device comprising supporting means for connection with the body, a plurality of flexible tubes carried by the supporting means and having enlarged compressible parts which bear against the body and are compressed when the wearer of the device breathes, flexible header tubes connected with the opposite ends of the first-named tubes and serving to place all of the tubes in communication, a liquid con-

tainer carried by the supporting means and connected with the header tubes and having spaced inner and outer walls, and a self-contained heater arranged inwardly of the inner wall of the container for transmitting heat to the liquid within the container.

6. A body warming device comprising supporting means to be mounted upon the body, a plurality of heat transfer tubes secured to the supporting means and extending longitudinally of the body between the shoulders and hips, the tubes being provided at longitudinally spaced intervals with enlarged compressible portions for contact with the body and adapted to be compressed during breathing, upper and lower headers connected with the upper and lower ends of the heat transfer tubes, a double walled liquid container secured to the supporting means and formed to provide a pocket inwardly of the walls of the container, said container having opposite ends connected with the headers, a chemical heater mounted within the pocket of the container, and check valves mounted within the heat transfer tubes to permit liquid to flow therethrough in one direction only.

7. A body warming device comprising a jacket to be worn upon the trunk portion of the body, means carried by the jacket for drawing the jacket tightly about the body of the wearer, a plurality of flexible heat transfer tubes secured to the inner side of the jacket next to the body, each heat transfer tube having a plurality of longitudinally spaced enlarged compressible portions which bear against the body and are compressed and expanded during breathing, common headers connected with the opposite ends of the heat transfer tubes so that the tubes are in communication, and self-contained heating means mounted upon the jacket for heating liquid within the heat transfer tubes.

8. A body warming device comprising a jacket adapted to be bound tightly about the body of the wearer, a plurality of flexible heat transfer tubes secured to the inner side of the jacket and extending between the shoulder and waist portions of the body, each flexible tube having a plurality of longitudinally spaced compressible bulb portions which bear against the body and are compressed and expanded during breathing, the bulb portions of adjacent flexible tubes being staggered longitudinally of the tubes so that they interfit and cover the maximum area of the body, check valve means for each flexible tube to permit liquid to flow in one direction only within the tube, and self-contained heating means mounted upon the jacket for heating the liquid within the tubes.
